UNITED STATES PATENT OFFICE.

LOUIS Y. McCONNELL, OF ROCHESTER, NEW YORK.

VOTING-MACHINE.

SPECIFICATION forming part of Letters Patent No. 570,812, dated November 3, 1896.

Application filed July 31, 1895. Serial No. 557,799. (No model.)

To all whom it may concern:

Be it known that I, LOUIS Y. McCONNELL, a citizen of the United States, and a resident of the city of Rochester, in the county of Monroe and State of New York, have invented a certain new and useful Voting-Machine, of which the following is a specification, reference being had to the accompanying drawings, in which—

10 Figure 1 is a rear elevation of one of my machines. Fig. 2 is an elevation of a portion of the front thereof. Fig. 3 is a side elevation of one of the handles. Figs. 4, 5, and 6 are respectively rear, side, and front elevations of one of the register-actuating disks. Figs. 7 and 9 are respectively rear elevations of one of the independent balloting devices, shown in different positions. Fig. 8 is a side elevation of one of the independent balloting devices, shown in the same position as Fig. 9, with the guard-plate removed. Fig. 10 is a cross-section on the line 10 10 of Fig. 1, but showing the register and name-holder in side elevation. Fig. 11 is a 25 rear elevation of a portion of the question-voting devices. Fig. 12 is a side elevation of one of the independent balloting devices and the connected parts. Fig. 13 is a central section of an independent ballot-case. 30 Figs. 14 and 15 show modifications of the mechanism for releasing the register-actuating disks, and Figs. 16, 17, 18, and 19 show modifications of the lock-out and returning mechanism.

35 The object of my invention is to produce a simple and efficient voting-machine having, among other things, means for selective voting, group mechanism, question-voting mechanism, and independent balloting mechanism.

40 My invention consists in the mechanisms, combinations, constructions, and arrangements of parts hereinafter set forth and claimed.

45 In the drawings, A is a vertical plate, preferably of iron or steel, which supports all the parts and which is perforated by a series of holes, through which the stems or bolts b^2 of the keys or handles B are passed, and which is also perforated, when independent balloting devices are used, by a series of apertures B', Fig. 2, for the insertion of the ballot-cases hereinafter described. The plate A

supports the working parts and divides the voting-booth into two parts, one of which is accessible to the voter and the other of which 55 is accessible only to the inspectors or other authorized officials. Each key or handle B is provided with a pin b , Fig. 3, which moves in a curved slot b' , (see Fig. 2,) in the outward face of a boss B^2 , fixed upon the front 60 face of the plate A. The ends of the slot form stops to limit the movement of the handle. Through the handle B and boss B^2 passes a bolt b^2 , having a square shank, which is fixed in a square hole through the handle 65 B, and passes through a round hole in the boss B^2 and plate A. On the end of the bolt b^2 is fixed a register-actuator composed of a disk C, (see Figs. 4, 5, and 6,) which bears two lugs, which I prefer to make as pulleys 70 C' C' to decrease friction, arranged on opposite sides of the center of the disk. These pulleys are pivoted to the disk by bolts c and turn freely upon the bolts. On the face of the disk, opposite to the face bearing the 75 pulleys C', is a stop or cam c', (see Figs. 5 and 6,) which actuates the mechanism which operates the registers or counters, as herein-after explained.

An equivalent for the disk and pulleys is 80 found in any device in a register-actuator which bends the band or chain hereinafter described so as to take up all the slack thereof.

The register-actuators are arranged on the back of the plate A in proper relation to the 85 keys or handles B and are preferably arranged in horizontal lines, as best shown in Fig. 1, so that the series of register-actuators in the highest horizontal line represent the candidates of one political party, such 90 as the Republican, the second line the candidates of the Democratic party, the third line the candidates of the Prohibition party, and so on, according to the number of parties having candidates in the field. The lowest horizontal row of disks in Fig. 1 represents a row of independent balloting devices for the use of voters who do not wish to vote for any of the regular nominees of any party. In Fig. 1 the five disks to the left in the lowest row represent such independent balloting devices. Upon the plate A are fixed a series 100 of brackets D. (Shown in Figs. 1 and 10.) These brackets are set vertically above the

centers of a vertical row of the disks C, and to each bracket is fastened a flexible band or chain D'. This chain passes between the pulleys C' C' of each of the disks. At the 5 bottom of each chain is fastened a suitable tension device, such as the weight D², which serves to keep the chain taut. When the chain is taut and straight, the weights D² are at their lowest positions.

10 The series of actuators, with each of which a band or chain engages, represents the several candidates of all the parties in the field for the same office, as, for instance, the vertical row marked 1, to the left in Fig. 1, represents the candidates for mayor of the three parties, Republican, Democratic, and Prohibition, and an independent balloting device for other persons for the office of mayor. Rows Nos. 2, 3, 4, and 5 represent the candidates for other offices, with a like independent balloting device in each row. On the plate A and below the independent balloting devices are a series of guides d, through which the chains D' pass, and which also 25 serve as stops for the upward movement of the weights D². If now one of the disks representing a candidate for mayor is turned by means of the handle B in the direction shown by the arrows, the chain D' is flexed by the 30 pulleys C', as illustrated in Fig. 1, and the corresponding weight D² is lifted. The weight D² is adjustably fixed upon the chain D' by the set-screw d³ and is so set thereon that when any one of the disks C, engaging with 35 a chain in the rows or series Nos. 1 to 5, inclusive, is turned to the limit of its motion the weight will abut against the guide d and cannot be further raised. It will thus be seen that when the weight D² is properly adjusted upon the chain only one of the series 40 of actuators engaging with that chain can be turned, for after one actuator has been turned the chain will be taut and another actuator in the series is prevented by the taut chain 45 from further flexing the chain, since all the slack of the chain has been taken up by the operation of the first actuator. Hence the flexible band or chain D' is capable of being flexed only to a fixed degree, and each actuator 50 is adapted to flex the band to a definite extent, and when the band is flexed to said fixed degree by the operation of any actuator the unoperated actuators are held against operative movement.

55 In Fig. 16 is shown a pair of weights D², holding the band D' under longitudinal tension, and a pair of stops d for guiding the band and for limiting the extent of its movement, according as the weights D² are adjusted 60 thereon. On each register-actuating disk C, instead of the pulleys C', is a plate C², having a slot through which the band passes and which, when the disk C is turned, flexes the band by bending it at its two separated points 65 of emergence from the slot at the ends of the plate. In this modification the weights D² are adjusted upon the band D', so that the

total possible flexing of the band is only sufficient to permit the turning of one or more of the disks as predetermined by the adjustment of the weights thereon.

In Fig. 17 is shown a modification wherein the disks C engage a band D', passing through stops d, fixed upon the plate A, and on one or both ends of the band are fastened clips d⁴, 70 which, by coming in contact with the stops d, serve to limit the amount of flexing of the band. In the clips d⁴ are also fastened springs d⁵, which are fastened in fixed brackets d⁶. These springs keep the band under longitudinal tension, but may yield to the extent 80 permitted by the clips and stops to allow the predetermined number of disks C (one or more) to be turned to actuate the register.

In Fig. 18 the band D' is shown having its 85 ends adjustably fixed in stationary brackets d⁶. The slack in the band is sufficient to permit one or more of the disks C to be turned as predetermined. A weight or spring d⁷ is attached to a yoke d⁸, which carries a roller 90 d⁹, resting on the band, and I thus apply the tension for returning the disks to initial position in this form of my device.

Fig. 19 shows a modification of my device when applied to a voting-machine having 95 push-buttons as register-actuators instead of the rotary disks hereinbefore described. In this case I provide the flexible band D', the stop d, and the weight D², as before. Upon the plate A are fastened a series of guides M, 100 preferably bearing antifriction-rollers m. The shank N of the push-button is slotted to permit the band D' to pass through it, and also preferably bears an antifriction-roller n. When the band is taut and straight, the shank 105 of the push-button is forced outward and the parts have the position shown with respect to the lower push-button in the figure. When a push-button is pressed in, the band is flexed by the pressure of the roller n upon it. The weight D² is lifted and comes in contact with the stop d. A suitable retaining device, such as is well known in this art, holds the operated push-button against a second operation until properly released, while the remaining 110 taut portion of the band D' prevents the operation of any other push-button in the series. The pawl E' is pivoted to the plate A, the shank N has a notch n', into which the pawl drops when the push-button is operated, and 115 a bar or band e², provided with stops e³, operates the tails e' to release the pawls, substantially as shown in Fig. 14.

Each of the disks C has a notch c³ in its periphery. Suitably pivoted to the plate A 125 are a series of pawls E, arranged above the several disks and so placed that when the disk C has been moved to the proper extent the pawl will drop into the notch c³ and will prevent a backward rotation of the disk, 130 whereupon, the disk being locked against further rotation in the direction of the arrows in Fig. 1, by reason of the weight D² abutting against the stop d, and since the pawl E, en-

gaging in the notch c^3 , prevents backward movement, the disk becomes locked against further movement in either direction.

F F are a series of vertical releasing-rods 5 moving in suitable guides upon the plate A and bearing a pair of pins $f f'$ for each pawl E, one pin above said pawl and one below. (See Figs. 10 and 11.) The upper pin prevents any accidental throwing of the pawl too far away from the disk C, and the pin f' is so set as to prevent the pawl from dropping fully to the bottom of the notch c^3 , but permitting it to engage sufficiently in said notch to hold the disk C against backward rotation. This 15 arrangement is for the purpose of preventing fraudulent jarring of the pawl out of the notch c^3 . The rods F F are pivoted to a series of arms F', (see Fig. 10,) which are connected to a transverse bar F², capable of rotation in suitable bearings f^2 , fastened to the plate A above the whole series of voting devices. If the rod F² is rotated in the direction of the arrow in Fig. 10, all the rods F will be lifted and the pins f' , pressing against the pawls E, will release all the operated pawls from the operated disks C in the machine, and the weights D² will, by their tension upon the chains D', straighten all the flexed chains, which, acting upon the pulleys 25 C', will automatically return all the operated disks C to their initial positions. Hence each 30 flexible band and the tension devices coöperating with it constitute a lock-out and returning device for the actuators. The rod F² is actuated by an attendant in charge of the voting-booth, which contains the voting-machine, or it may be operated in a manner well understood by the movement of the door of the booth. A lever F³ upon the shaft F² is 35 provided for the purpose of actuating the shaft.

In Fig. 14 is shown a modified form of the retaining-pawls for the register-actuating disks and of the mechanism for releasing the pawls therefrom. The disk C has the notch c^3 , as in the form heretofore described. The pawl E' is pivoted directly upon its own register G and has an upwardly-extending tail e' , which is perforated near the end. Through the tail 50 of each pawl of a series passes a bar or band e^2 , bearing a series of adjustable stops e^3 . When the bar or band e^2 is moved in the direction of the arrow, the stops e^3 come in contact with the tails e' of the pawls and lift the pawls E' out of engagement with the notches 55 c^3 . This bar or band e^2 may be operated in any suitable manner, as, for instance, if it is a flexible band, such as a chain or wire cable, it may be wound upon a pulley e^4 upon a 60 shaft e^5 , which is rotated to an extent sufficient to release the pawls by the opening of the door through which the voter passes out of the booth. A tension device, such as a spring or a weight passing over a pulley, is 65 used to keep the bar or band pulled in the direction opposite to that of the arrow, or the bar or band e^2 may be continuous and have

flexible portions passing around two pulleys, like e^4 , one at each side of the machine, and being connected to the pulley the stops e^3 are 70 positively moved both to release the pawls from the disks and to allow the pawls to drop back into normal position. A pin e^6 for each pawl prevents the pawl from dropping too far into the notch c^3 . The form just described 75 is my preferred form.

In Fig. 15 the disks C are of the same form as hereinbefore described, but the pawls E² for engagement therewith are pivoted to a bar E³, which extends transversely across the 80 machine and moves in slotted guides E⁴. The slots in the guides not only permit the bar to move longitudinally, but also to rise and fall to the proper degree. Upon the bar E³ there is a guide E⁵ for the free end of each pawl to 85 limit its motion. At each end of each bar is a link E⁶, which is pivoted to the bar and to the plate A. These two links E⁶ are parallel and guide the bar so as to cause it to move both longitudinally and vertically, as shown 90 in full and dotted lines in Fig. 15. To the end of the bar E³ is also fixed a pair of toggle-links E⁷ and E⁸, one of them, E⁸, being pivoted to the plate A. A lug E⁹ upon one of these links, as E⁷, rests upon the other link 95 E⁸ when the two are in line, and thus holds the links in line, as shown in full lines in Fig. 15, and holds any operated pawl rigidly in place against the pressure of its disk. A releasing-bar E¹⁰, operated in any suitable manner by the door through which the voter passes out of the booth, is connected to the toggles 100 E⁷ and E⁸ at the point where they are pivoted together. If this bar is pulled upward, it bends the toggles, and as the end of the link E⁸ is fixed to the plate A the toggles move 105 into the position shown by dotted lines and at the same time pull the bar E³ in the direction shown by the arrow, thus pulling the pawls in a direction to disengage them from 110 the notches c^3 of the disks C, and at the same time the links E⁶, being pivoted to the plate, compel the bars to rise, thus assisting in this disengagement.

Upon the plate A and adjacent to each disk 115 C (except in the independent balloting devices) is a register G. This register is of any suitable construction adapted to count the number of times which the key or handle B is operated. In the form shown in the drawings an arm g extends outward from the interior of the register-case, so placed that when a disk C is turned so far that the pawl E can drop into the notch c^3 the plate or lug c' presses the arm g upward and actuates the 120 register. The notch c^3 in the disk C is made with one side in a radius extending from the center of the disk and with the other side at an angle to said first side, as shown in Figs. 4, 6, 7, and 9, and the disk is capable of revolution so far as to allow the pawl to fall into the notch and then to permit a slight further movement of the disk. The movement of the disk between the point where the pawl first 125 130

falls into it and the point to which it may further be moved preferably measures the extent of movement from the first engagement of the plate c' with the arm g to the position 5 of full movement of the arm g to operate the register; but the actuator may be adjusted so as to operate the register as soon as the pawl engages the disk.

With the constructions thus far described 10 a voter may vote for any one of a series of candidates for the same office, but for no more than one of such candidates.

I also provide what is called "straight-ticket mechanism" for voting for all the candidates of any particular party by the operation 15 of a single handle or key, as follows: Transversely across the machine and adjacent to the row of disks C , representing the candidates of a single party, are a series of 20 longitudinally-sliding rods H , moving in suitable guides h . At one side of the machine each rod H is provided with a rack h' , (shown in Fig. 1,) and with this rack meshes a segment H' , which is operated by a handle or 25 key on the front of the machine connected with a short shaft h^2 , which bears the segment H' . Upon disks C are fastened a series 30 of levers C^2 , which must turn whenever the disk turns. These levers C^2 pass through the 35 rods H and against bearings h^3 , formed in or on the rods. (See Fig. 5.) If now one of the segments H' is turned in the direction of the arrow in Fig. 1, the levers C^2 will press against the bearings h^3 and will turn the disks with 40 which the levers are connected until the pawls E fall into the notches c^3 . This operation actuates all the registers corresponding to the disks which have levers upon them.

The so-called "group mechanism" is for 45 use where a party has a series of candidates in the field for a single office, as, for instance, four constables may be nominated by each party, of which only two can be elected. It becomes necessary therefore for a free ballot that two of the whole number of candidates of the several parties for the office of constable may be selectively voted for. I therefore arrange a single band or chain D' , passing through the pulleys of all the disks 50 used to vote for constables, as shown in the rows 6, 7, 8, and 9 of Fig. 1, and so arrange the stops that when any predetermined number of actuators shall be turned the stop prevents further operation of any other disk. I 55 accomplish this, as shown in Fig. 1, by fixing the chain at one end or both ends to the brackets D and by arranging the stops D^2 at the bottom, passing the chain around pulleys D^4 D^5 D^6 and connecting the weights D^2 to 60 yokes D^7 on the lower pulleys. The adjustment of the weights D^2 may be made so as to permit the turning of one, two, or more of the disks through which the chain passes. I thus avoid the use of protective doors, step-by-step devices, and provide a simple, easily-adjusted and easily-variable device for the 65 group mechanism. The group mechanism is

not connected with the straight-ticket mechanism for obvious reasons.

The independent balloting mechanism is 70 shown at the bottom of the vertical rows Nos. 1, 2, 3, 4, and 5 in Fig. 1, and the specific details thereof are shown in Figs. 7, 8, 9, and 12. A disk J , provided with a handle B and bolt b^2 , is connected, as in the case of the balloting 75 devices hereinbefore described. The disk J has a notch c^3 , the pulleys $C' C'$, which engage the band or chain D' , as with the other voting devices, and a pawl E of the same kind and for the same purposes as above described. Each 80 disk J has a perforation j through it, which is partially surrounded by a curved shelf j' . (Shown in full lines in Figs. 8 and 9 and in dotted lines in Fig. 7.) The perforation j registers with the perforation B' in the front 85 plate A when the devices are in readiness for voting. These perforations are of suitable size to admit the ballot-holder K . (Shown in Fig. 13.) If this ballot-holder is inserted through the perforation B' , so as to rest upon the shelf j' , the disk J may be rotated just like the disks C . After the rotation of the disk J has occurred to the extent of the limit of its motion the curved shelf j' is turned so far as to permit the ballot-holder K to fall 90 into a receiving-box L . A curved shield J' prevents the ballot-holder K from falling out or from being pushed off the shelf j' until the disk J has been sufficiently turned. The turning of the disk J pulls up the weight D^2 100 until it is arrested by the stop d , whereupon none of the other disks C , which engage with the same chain D' , can be turned. Consequently a voter, after voting an independent ballot for his candidate for an office, cannot 105 vote a second time for the same candidate or for another independent candidate or for one of the regular nominees for that office. When a voter desires to vote for an independent candidate, he writes the name of his candidate upon a suitable piece of paper, which is inserted in the opened ballot-holder K , the cover of the ballot-holder is applied, and the whole ballot-holder is inserted through the perforation B' , the handle corresponding to 110 that independent balloting device is turned, the vote is discharged into the receptacle L , and the regular and independent devices are all locked as to the opportunity of voting for another candidate for that office. 115

An independent balloting device is considered as the full mechanical equivalent for any one of the registers set forth in the claims, so far as the operation of the key and of the lock-out and returning devices are concerned. 120

At the right hand of Fig. 1 are two columns of devices for question-voting, and in Fig. 11 is an enlarged rear view of a portion of the same. These devices are for use where questions, such as constitutional amendments, are to be voted for. G' is the register for registering the votes for one of such questions, and G^3 is the register for registering the votes against that question. These 125

registers are actuated by disks C, having the same attachments, retainers, and releasing mechanism as the disks for the registers G. The band or chain D⁸ is, however, preferably arranged horizontally, and each chain is attached to a lug D⁹ and passes between the pulleys C' C' of each disk relating to the same question, passes over a pulley D¹⁰, and thence downward through a guide and stop D¹¹ to the weight D¹², which is adjustable on the band or chain. As shown in Fig. 11, if the upper right-hand disk is turned the weight D¹² will be raised until it strikes the stop D¹¹, when the upper left-hand disk cannot be turned. The turning of the disk operates the register, and the pawl E, engaging with the disk, prevents further voting for or against that question until the pawl is released by the movement of the rod F, as hereinbefore described.

I provide also a stationary indicator for each key or handle. On the face of the plate A and immediately above each handle B is a card-holder, (see Figs. 2 and 10,) which in the form shown is a continuous bar having a series of perforations for displaying the names of the candidates or for a proper indication of the subject-matter to be voted for by means of the adjacent handle. This bar O is held to the plate A by means of bolts o, which are fastened by means of nuts on the rear side of the plate, the bolt-heads on the front of the plate being smooth, so that they cannot be unfastened by a voter. A lip o' (see Fig. 10) on the lower side of the bar O rests in and behind a groove in a bar O', which is held to the plate A by means of bolts o', which are, like the bolts o, fastened at the back of the plate, so that a voter cannot unfasten them. The bar O contains a series of glass plates, behind which the cards having the names of candidates or other subject-matter for vote are placed, so as to be changeable for different elections. Each register G is provided with lugs g² for holding a card which bears matter corresponding to the matter upon the card on the front of the machine adjacent to the handle B for operating the register.

The independent balloting devices may have card-holders on the front of the plate A like those above mentioned, but simply indicating the office, and they may have card-holding lugs g², but it is unnecessary to show these arrangements.

It is obvious that a weight need not be used as a stop for limiting the amount of the possible flexing of the band or chain, but that a separate stop, adjustable on the band, may be employed. It will be observed that in my device the bands or chains can be changed from one part of the device to another part thereof in order to adapt the machine to the varying circumstances of different elections, including enlargement or reduction of the number of actuators included in a group mechanism. For instance, the group-chain

may be fastened in any of the brackets D, and the yokes D⁷ may be set in any of the stops d, as tapped holes are provided for changing the positions of the stops. These holes may be filled with screws when not used. A series of supports D³ for wheels D⁵ permit the enlargement or diminution of the scope of the group mechanism.

It is thus seen that my voting-machine is extremely simple in its construction, is very strong, is certain in its action, is easily capable of enlargement or adjustment to suit any number of candidates or questions to be voted for, and is provided with devices for voting for regular candidates, with devices for voting for candidates selected from a single group or from a series of groups of plural candidates for the same office, with mechanism for voting for constitutional or other questions, and is further provided with independent balloting devices. Thus my machine has all the functions which are required in a voting-machine for any purpose at present known, and it cannot be cheated when properly adjusted. All the functions of these devices are performed by simple mechanism.

It is not intended to limit my claims to the specific forms of devices shown and described, but that the scope of claims should correspond with the novelty which my machine possesses as compared with the prior state of the art, and the claims are therefore not to be limited to the exact forms or combinations stated in them, but are to be as broadly construed as their terms and the doctrine of equivalents will permit.

What I claim is—

1. In a voting-machine, the combination of a flexible band normally held in tension and capable of being flexed only to a fixed degree, a series of independent registers, a corresponding series of register-actuators, one for each register, each actuator adapted to flex said band to a definite extent in order to operate its register, said band being located directly in the path of movement of each actuator, but free from fixed connection therewith, whereby, when said band is flexed to a fixed degree by the operation of a predetermined number of said actuators, the unoperated registers are prevented from being operated, and means for preventing a second actuation of any operated actuator until every operated actuator is returned to its initial position.

2. In a voting-machine, the combination of a flexible band normally held in tension and capable of being flexed only to a fixed degree, a series of independent registers, a corresponding series of register-actuators, one for each register, each actuator adapted to flex said band to a definite extent, in order to operate its register, said band being located directly in the path of movement of each actuator, but free from fixed connection therewith, whereby, when said band is flexed to a fixed degree by the operation of a pre-

determined number of said actuators, the unoperated actuators are held against operative movement, retaining means for holding each actuator when operated and said band and means for releasing said retaining means.

3. In a voting-machine, the combination of a flexible band normally held in tension and capable of being flexed only to a fixed degree, a series of independent registers, a corresponding series of register-actuators, one for each register, each actuator adapted to flex said band to a definite extent, in order to operate its register, said band being located directly in the path of movement of each actuator, but free from fixed connection therewith, whereby, when said band is flexed to said fixed degree by the operation of a predetermined number of said actuators, the unoperated actuators are held against operative movement, retaining means for holding each actuator when operated and said band, means for releasing said retaining means, and means for automatically returning every operated actuator to its initial position.

25 4. In a voting-machine, the combination of a flexible band, devices coöperating with said band for limiting the amount of the possible flexing thereof, a series of independent registers, a corresponding series of register-actuators, one for each register, each actuator engaging said band and adapted to flex said band to a definite extent, in order to operate its register, whereby, when said band is flexed to its full limit by the operation of a predetermined number of said actuators, the unoperated actuators are held against operative movement, a key and a fixed indicator for each actuator, a pawl for engaging each actuator and for holding the same when operated, means for releasing each operated pawl, and tension apparatus for actuating said band, to return each operated actuator when released, to its initial position.

5. In a voting-machine, the combination of a flexible band, devices coöperating with said band for limiting the amount of the possible flexing thereof, a series of independent registers, a corresponding series of register-actuators, one for each register, each actuator engaging said band and adapted to flex said band to a definite extent, in order to operate its register, whereby, when said band is flexed to its full limit by the operation of a predetermined number of said actuators, the unoperated actuators are held against operative movement, a key and a fixed indicator for each actuator, a pawl for engaging each actuator and for holding the same when operated, means for releasing said pawl, and means, of which said band is an element, for returning each operated actuator when released, to its initial position.

6. In a voting-machine, the combination of a flexible band, adjustable devices coöperating with said band for limiting and varying the amount of the possible flexing thereof, a series of independent registers, a correspond-

ing series of register-actuators, one for each register, each actuator engaging said band and adapted to flex said band to a definite extent, in order to operate its register, whereby, when said band is flexed by a predetermined number of said actuators to the full extent predetermined by said adjustable devices, the unoperated actuators are held against operative movement, and means for preventing a second actuation of any operated actuator until it is returned to its initial position.

7. In a voting-machine, the combination of a flexible band, adjustable devices coöperating with said band for limiting and varying the amount of the possible flexing thereof, a series of independent registers, a corresponding series of register-actuators, one for each register, each actuator engaging said band and adapted to flex said band to a definite extent, in order to operate its register, whereby, when said band is flexed by a predetermined number of said actuators to the full extent predetermined by said adjustable devices, the unoperated actuators are held against operative movement, retaining means for holding each actuator when operated, means for releasing the operated retaining means, and means for automatically returning each operated actuator to its initial position.

8. In a voting-machine, the combination of a flexible band, a fixed stop, a stop moving with said band and adapted to engage said fixed stop for limiting the amount of the possible flexing of said band, a series of independent registers, a corresponding series of register-actuators, one for each register, each actuator engaging said band and adapted to flex said band to a definite extent in order to operate its register, whereby, when said band is flexed by a predetermined number of said actuators to the full extent predetermined by said stops, the unoperated actuators are held against operative movement, and means for preventing a second actuation of any operated actuator until its return to its initial position.

9. In a voting-machine, the combination of a flexible band, a fixed stop, a stop moving with said band and adapted to engage said fixed stop for limiting the amount of the possible flexing of said band, a series of independent registers, a corresponding series of register-actuators, one for each register, each actuator engaging said band and adapted to flex said band to a definite extent in order to operate its register, whereby, when said band is flexed by a predetermined number of said actuators to the full extent predetermined by said stops, the unoperated actuators are held against operative movement, retaining means for holding each actuator when operated, means for releasing the operated retaining means, and means for automatically returning each operated actuator to its initial position.

10. In a voting-machine, the combination of a flexible band, a fixed stop, a stop moving with said band and adjustable thereon and adapted to engage said fixed stop for limiting 5 and varying the amount of the possible flexing of said band, a series of independent registers, a corresponding series of register-actuators, one for each register, each actuator engaging said band and adapted to flex said 10 band to a definite extent in order to operate its register, whereby, when said band is flexed by a predetermined and variable number of said actuators to the full extent predetermined by said stops, the unoperated actuators 15 are held against operative movement, and means for preventing a second actuation of any operated actuator until its return to its initial position.

11. In a voting-machine, the combination 20 of a flexible band, a fixed stop, a stop moving with said band and adjustable thereon and adapted to engage said fixed stop for limiting and varying the amount of the possible flexing of said band, a series of independent registers, 25 a corresponding series of register-actuators, one for each register, each actuator engaging said band and adapted to flex said band to a definite extent in order to operate its register, whereby, when said band is flexed by a 30 predetermined and variable number of said actuators to the full extent predetermined by said stops, the unoperated actuators are held against operative movement, retaining means for holding each actuator when operated, 35 means for releasing the operated retaining means, and means for automatically returning each operated actuator to its initial position.

12. In a voting-machine, the combination 40 of a flexible band, means for yieldingly holding said band under tension, devices coöperating with said band for limiting the amount of the possible flexing thereof, a series of independent registers, a corresponding series 45 of register-actuators, one for each register, each actuator engaging said band and capable of flexing said band to a definite extent, in order to operate its register, whereby, when said band is flexed to the limit of the possible 50 flexing thereof by a predetermined number of said actuators, the unoperated actuators are held against operative movement, a key and a fixed indicator for each actuator, retaining means for holding each actuator when 55 operated, and means for releasing the operated retaining means, whereby the means for holding said band under tension returns each operated actuator to its initial position upon release of the retaining means.

60 13. In a voting-machine, the combination of a flexible band, capable of being flexed only to a fixed degree, a series of independent registers, a corresponding series of rotary register-actuators, one for each register, each actuator having means for engaging said band at two separated points and thereby adapted to flex said band to a definite extent when op-

erated, whereby, when said band is flexed to said fixed degree by a predetermined number of said actuators, the unoperated actuators 70 are held against operative movement, retaining means for holding each operated actuator, means for releasing said retaining means, and means for rotating each operated actuator to its initial position.

75 14. In a voting-machine, the combination of a flexible band capable of being flexed only to a fixed degree, a series of independent registers, a corresponding series of rotary register-actuators, each having a pair of pulleys, 80 as C', thereon, one being at one side of the center of rotation of said actuator, and having said flexible band between said pulleys, whereby, when said band is flexed to said fixed degree by the rotation of a predetermined number of said actuators, the unoperated 85 actuators are held against operative movement.

90 15. In a voting-machine, the combination of a series of independent registers, a corresponding series of register-actuators, each having means of engaging with a retainer, a retainer attached to each register and adapted to engage the corresponding actuator, a lock-out and returning mechanism engaging each actuator of said series and adapted to permit the operation of a predetermined number of said actuators and to prevent the operation of the unoperated actuators in excess of said predetermined number and to return 100 said actuators to initial position, a bar or band adapted to engage said retainers to release the same from said actuators, and operating mechanism for moving said bar or band.

105 16. In a voting-machine, the combination of a series of independent registers G, a corresponding series of pawls or retainers, as E', each having a tail e' and each pivoted to its register, a corresponding series of register-actuators having means, as a notch, for engaging, when operated, with said pawl or retainer, a bar or band e² passing through perforations in the tails e' and carrying adjustable stops e³, means for moving said bar or band to cause said stops to engage said tails and to release said pawls or retainers from said notches, means for preventing the operation of all except a predetermined number of actuators in said series and means for returning the operated actuators to initial position.

110 17. In a voting-machine, the combination of a series of registers, a corresponding series of register-actuators, a flexible band engaged 125 and flexed by each actuator when operated to actuate its register, and means for yieldingly holding said band under longitudinal tension, whereby, upon releasing an operated actuator, the actuator is automatically returned to its initial position by said band and tension device.

130 18. In a voting-machine, the combination of a series of registers, representing all the

candidates of the different parties for election to an office, a corresponding series of register-actuators, and an automatic lock-out and returning device engaging each actuator in said 5 series, said lock-out and returning device being adapted to return all the operated actuators of the series to their initial positions upon release of said actuators and before any other actuator can be operated.

- 10 19. In a voting-machine, the combination of a series of registers, representing all the candidates of the different parties for election to an office, a corresponding series of register-actuators, an automatic lock-out and returning 15 device engaging each actuator in said series, the lock-out and returning device being adapted to return all the operated actuators of the series to their initial positions upon release of said actuators and before any other 20 actuator can be operated, devices for holding each actuator when operated and means for releasing said holding devices.

20. In a voting-machine having a supporting plate-bearing voting apparatus and provided with a series of apertures for the insertion of ballot-cases, an independent balloting mechanism consisting of a rotary actuator on one side of said plate, having a shelf thereon normally registering with one of said apertures and adapted, when the actuator is in 25 normal position, to receive a single ballot-case and when rotated to discharge said case, a handle or key on the other side of said plate attached to said actuator, means, as a plate rotating with said actuator, for closing said 30 aperture when the actuator is rotated, a receiver for said ballot-cases, and means for automatically returning said actuator to its normal position.
